BACK SPACING MECHANISM OPERATING
MEANS FOR TYPEWRITING OR LIKE
MACHINES

John F. Kloski, Hartford, and William H. Kupper,
West Hartford, Conn., assignors to Royal Type-
writer Company, Inc., New York, N. Y., a cor-
poration of New York

Application September 13, 1949, Serial No. 115,542

9 Claims. (Cl. 197—91)

1

This invention relates to back spacing mechanism operating means for typewriting or like machines, and more particularly to means for operating back spacing mechanism by power supplied, e. g. by an electric motor.

An object of the invention is to provide a new and improved train of driving connections between a power generating mechanism and the back spacing mechanism of a typewriter or like machine, the connections including cushioning means of novel construction adapted to minimize abruptness of operation of the back spacing mechanism, avoid jamming of the parts, and minimize noise and vibration.

Another object of the invention is to provide, for the operation of a back spacing mechanism, a train of connected elements including a toggle device adapted to cause the back spacing mechanism to start the carriage on its back spacing movement gradually, to then move it more rapidly, and to then decelerate it near the end of its back spacing movement.

A further object of the invention is to provide means of the character referred to including a spring cushioned toggle device for transmitting drive to the back spacing mechanism.

Other objects of the invention will become apparent from a reading of the following description of a preferred embodiment of the invention, the appended claims, and the accompanying drawings, in which:

Figure 1 is a view, partly in elevation and partly in vertical section, fore and aft of a typewriter embodying the invention, showing only some of the conventional or standard typewriter parts in order to illustrate the application of mechanism embodying the invention to a typewriter construction, the parts being shown in their normal or inactive positions;

Figure 2 is a fragmentary, substantially horizontal sectional view on the line 2—2 of Figure 1, drawn on an enlarged scale;

Figure 3 is a fragmentary detail elevational view showing a cushion lever and toggle construction with the parts in operated positions;

Figure 4 is a fragmentary view, partly in vertical section on the line 4—4 of Figure 1 and partly in elevation, showing parts of an escapement mechanism and a back spacing mechanism in their normal or inactive positions; and

Figure 5 is a fragmentary view, partly in vertical section and partly in elevation, showing the escapement and back spacing mechanisms illustrated in Figure 4, but with the parts in operated or active positions.

2

The invention may be embodied in typewriters or like machines of various kinds. For the purposes of illustration, the invention is shown as being embodied in an office type typewriter having, except for the power generating and transmitting mechanism to be described, many features in common with the well known Royal Standard typewriter. The drawings show only enough of the standard or known typewriter construction to assist in illustrating the manner in which mechanism embodying the invention may be coordinated with other parts of a typewriter construction.

The known construction illustrated includes a main frame A on which a carriage B equipped with a platen C is mounted for letter spacing and return movements by means of a top rail 1 secured to the carriage, and rolling upon balls 2, which in turn are adapted to roll on a frame-mounted bottom rail or track 3.

The carriage may be driven toward the left, that is, in the letter-spacing direction, by any suitable mechanism, for example, by a spring barrel 4 and draw band 5 of known or suitable construction.

For controlling the feeding of the carriage in letter-spacing direction to take place by letter space increments, the carriage is equipped with a rack 6 cooperable with an escapement mechanism generally designated D. The rack 6 is carried by a bail 7 having arms 8—8 pivoted on the carriage at 9—9 and urged by springs 10—10 to rock counterclockwise as viewed in Figure 1 so as normally to hold the rack in engagement with an escapement pinion 11. The bail 7 and rack 6 may be swung upwardly by any suitable means (not shown) so as to disengage the rack 6 from the pinion 11 to enable the carriage to be shifted manually in the usual manner. The pinion 11 is coupled by a ratchet device (not shown) with an escapement wheel 12 journaled at 13 on an escapement frame or bracket 14.

The bracket 14 is equipped with cone-shaped bearing screws 15—15 extending into conformingly shaped bearing recesses in mounting ears 16—16 integral with an oscillatable escapement rocker plate 17. The plate 17 is equipped with the usual fixed dog 18 and limber dog 19 pivoted on the plate as at 20, and urged counterclockwise as viewed in Figures 4 and 5 by a spring 21 interposed between a heel 22 on the limber dog and an ear 23 on the rocker plate 17. An abutment screw 24 has threaded connection with a boss or lug 25 on the back of the plate 17, and can be adjusted for determining the limit of

rocking of the limber dog 19 when the latter is engaged by a tooth of the escapement wheel 12. An escapement wheel check pawl 26 pivoted at 27 on the rocker plate 17, is urged counterclockwise by a spring 28 interposed between ears 29 and 30 on the pawl 26 and plate 17 respectively.

When the rocker plate 17 is oscillated back and forth, the dogs 18 and 19 will cooperate with the escapement wheel 12 in a well known manner for effecting the desired letter-spacing incremental movements of the carriage.

With the exception of power mechanism for operating it, the back spacing mechanism may be of known construction, and, as shown, is similar to the back spacing mechanism embodied in Royal Standard manually operated typewriters. As shown in Figure 4, a vertically movable thrust link 31, adapted to be operated by power in a manner to be described later, is pivoted at its upper end, as at 32, to a bell crank lever 33 mounted to rock about a pivot 34 on a fixed bracket 34^a. Also mounted to rock about the pivot 34, and independently of the bell crank 33, is a rock arm 35, the upper end of which is pivoted to a thrust bar 36, as at 37. The bar 36 is bifurcated to provide upper and lower arms 36^a and 36^b. The upper arm 36^a is provided with a pin 38 which is received in a slot 39 formed in a bracket 40 secured to the escapement bracket or frame 14, and is formed with an upwardly extending tooth 41 adapted to cooperate with the teeth on the rack 6 in a manner to be described later. The lower arm 36^b of the bar 36 extends behind the bracket 40 as viewed in Figure 4, and the upper arm 36^a extends in front of the bracket 40 so that the arms 36^a and 36^b, being disposed on opposite sides of the bracket 40, guide the thrust bar 36 for reciprocation in the direction of carriage travel. For translating rocking of the bell crank 33 first into rocking then into reciprocation of the thrust bar 36, the bell crank is formed with a heel 33^a adapted to engage a projection 36^c on the thrust bar 36. A spring 42 interposed between a pin 43 on the bar 36 and an arm 44 on the bracket 40 normally maintains the thrust bar 36 and rock arm 35 in the positions shown in Figure 4.

An escapement wheel stop 45 is slotted to receive the pin 43 on the bar 36 and an adjustment locking screw 46, also carried by the bar 36, the arrangement being such that the stop 45 can be variably positioned longitudinally with respect to the bar 36, and then locked in adjusted position.

A rack lock lever 47 is mounted to rock on an adjustable pivot pin 48 carried by the bracket 40 and is formed with an arcuate upper end part 47^a overlying the front bar of the bail 7 but normally being maintained free of engagement with the bail bar by a spring 49 interposed between an ear 50 on the rack lock 47 and an ear 51 on the bracket 40.

Normally the parts are in the positions shown in Figure 4. During typing, the escapement mechanism D is operated in the usual manner to enable the escapement wheel 12 and pinion 11 to rotate step by step in the direction of the arrow a to effect incremental letter-spacing movements of the carriage. In order to back space the carriage incrementally the thrust link 31 is moved upwardly in a manner described hereinafter so as to rock the bell crank lever 33 and arm 35, and thereby move the thrust bar 36 toward the right as viewed in Figure 4.

During the first part of the rightward movement of the thrust bar 36, the pin 38 will move away from the inclined left end of the slot 39 in the bracket 40 so that the bar 36 will be free to be moved upwardly by the spring 42 and by the turning moment imposed on the bar 36 by the heel 33^a of the bell crank lever 33. In this way the tooth 41 on the bar 36 will be moved into a tooth interspace on the escapement rack 6. Also during the rightward movement of the bar 36, the right-hand end of the thrust bar lower arm 36^b will engage the rack lock 47 and swing it clockwise about its pivot so as to move its upper arcuate portion 47^a into engagement with the top of the bail 7, thereby locking the bail against upward movement. At the same time the escapement wheel stop 45 will be moved into the position shown in Figure 5 so as to prevent reverse rotation of the escapement wheel 12. Continued movement of the thrust bar 36 toward the right, with its tooth 41 in engagement with the rack 6, will move the carriage one letter space toward the right, that is, in the return direction, as will be permitted by the ratchet coupling between the escapement wheel 12 and pinion 11. When the parts are returned from the positions shown in Figure 5 to the normal positions shown in Figure 4 by downward movement of the thrust link 31, the ratchet coupling between the escapement wheel and pinion will hold the carriage in the back-spaced position to which it has been moved.

In general, the parts described so far do not, in themselves, constitute the present invention. The invention resides in other parts to be described, and combinations of such other parts with each other and with parts already described.

Broadly considered, vertical reciprocation of the thrust link 31 and consequent back spacing of the carriage are effected by power-driven means, generally designated E, which are made effective by depression of a manually operable back spacing key F. Power is transmitted from the power-driven means E through a train of driving connections G. The construction and arrangement of the parts is such that, upon depression of the back spacing key F, a quickly generated power impulse is transmitted through a cushion device embodied in the train of connections G, to the thrust link 31 so as to raise the latter and operate the associated back spacing mechanism in the manner previously described.

The power-driven mechanism E is generally similar to but embodies improvements in mechanism disclosed in the copending application of William H. Kupper, Serial No. 6,066, filed February 3, 1948, now Patent No. 2,567,945, dated September 18, 1951. It includes a driving element, which operates continuously, and controllable driving connections, which normally are inoperative or ineffective, but which may be conditioned by the operator to effect operative driving connection between the continuously moving driving member and the train of connections G. The driver preferably is constituted by a continuously rotating element, more particularly a toothed snatch roll or bar 52, which may be of known form, and which is adapted to be driven in the direction of the arrow b in Figure 1 by any suitable means, but preferably by an electric motor (not shown).

The means for transmitting drive from the driver 52 to the connections G includes an actuator 53 which extends fore and aft of the typewriter and above the member 52. The actuator 53

is pivoted as at 54 to a lever 55 at a point off-set relatively to the pivotal mounting 56 of the lever on a fixed frame cross bar 57. The actuator has a forwardly extending part 58 projecting under an abutment or guide plate 59 mounted on the frame A, to extend parallel to the snatch roll 52. A spring 60, interposed between the front end of the actuator 53 and an anchor plate 61, yieldably urges the actuator to rock clockwise, and thus normally maintains the actuator in the position shown in Figure 1 with its front end part 58 bearing against the abutment or guide plate 59. Another abutment 62 is disposed below the abutment 59, and is slotted to receive and guide the lower extremity of the actuator part 58 for sliding movements. The lever 55 normally is held in its inactive position, shown in Figure 1, by a returning spring 63 interposed between an ear 64 on the lever and an anchor plate 65 mounted on the fixed cross bar 57 by screws, one of which is shown at 66. The lever 55 has a stop projection 67 engageable with a fixed stop strip 68 for limiting the returning movement of the lever under the urge of the spring 63.

In order to apply a power impulse to the train of driving connections G, the actuator 53 is operatively but indirectly connected to the driving member 52, the actuator itself never engaging the driving member. Mechanism for bringing about this operative connection includes an interponent pawl element 69, pivoted as at 70 on the actuator. A spring 71, anchored to the actuator 53 and connected to the pawl 69, biases or urges the latter to rock clockwise so as to move its double toothed nose 69a into engagement with the snatch roll 52. Normally, the pawl is maintained out of engagement with the snatch roll by the restraining action of a control element or trigger 72 which is pivoted as at 73 on the actuator 53. In the normal position of the trigger, its rear end engages a holding surface 74 on the pawl so as to prevent the spring 71 from rocking the pawl 69 into drive-transmitting engagement with the driving member 52. The pawl 69 is formed with an inclined resetter cam face 75 which is located just below the holding surface 74, and which is acted upon by the trigger for rocking the pawl counterclockwise, and thus resetting it in normal, inoperative position.

Operator controlled means for bringing about operative driving connection between the driver 52 and the actuator 53 includes the manually operable back spacing key F pivoted as at 76 on the frame A. The key F has an upward projection 77 disposed behind an arm 78 of an operating lever 79, pivoted as at 80 on a frame-mounted cross bar 81. The lever 79 has another arm 82 on which a limber dog or flipper 83 is pivoted at 84. A spring 85 urges the limber dog 83 to rock clockwise to yieldably retain it in its normal position of rest against a limit stop 86 on the lever arm 82. The dog 83 can swing counterclockwise from the position shown in Figure 1, but cannot move clockwise from this position. A returning spring 87, interposed between the key F and a short arm 88 on the lever 79, yieldably holds the lever 79 and the key F in their normal positions. When the parts are in their normal positions the spring 87 holds the lever 79 so that the lower end of the limber dog 83 overlies a contact ear 89 on the actuator 53, and holds the key F so that a forward projection 90 on the key bears against a cushion stop 91.

In operation, when the back spacing key F is depressed, the lever 79 is rocked clockwise to

cause the flipper 83 to push the actuator 53 downwardly to an initial extent sufficient to bring the trigger 72 into engagement with the abutment 62. This causes the trigger to be rocked clockwise about its pivot 73, so as to release the pawl 69, which is then moved by the spring 71 into engagement with the snatch roll 52. The snatch roll then drives the pawl 69 and actuator 53 as a unit so as to rock the lever 55 and operate the back spacing mechanism through the train of connections G. When the pawl 69 is cast off from engagement with the snatch roll 52, the spring 60 lifts the actuator 53 to bring the trigger 72 into engagement with the upper, trigger-resetting abutment 59. This causes the trigger 72 to be rocked counterclockwise, so as to move its rear end against the resetting cam face 75 of the pawl 69, thereby restoring the latter to its inactive position. The 20 parts of the mechanism E will then be returned to their normal positions by the spring 63.

Means are provided for adjusting or varying the amount of driving impulse generated by the power mechanism E. This variation or adjustment is effected by variably limiting the extent to which the teeth on the actuator pawl nose 69a enter tooth interspaces on the snatch roll 52 under the urge of the spring 71 when the restraint of the trigger 72 on the pawl 69 is discontinued. In the form shown, the actuator 53 is provided with a downwardly extending stop element or finger 92 which is disposed in front of and normally out of contact with a downwardly extending stop part, heel, or finger 93 on the pawl 69. When the pawl 69 is rocked clockwise by the spring 71 so as to move the teeth on the pawl nose 69a into snatch roll tooth interspaces, the pawl stop 93 moves toward the actuator stop 92, which may be so positioned as to be engaged by the stop 93 to arrest rocking of the pawl 69 before the pawl teeth move to the roots of the snatch roll tooth interspaces. By variably positioning one of the stops 92, 93, e. g., by bending the stop 92 towards or away from the stop 93, the extent to which the pawl teeth enter the tooth interspaces on the snatch roll can be varied. Consequently, the angle through which the snatch roll rotates while in contact with the pawl, which determines the amount of driving 40 of the pawl 69 and actuator 53 by the snatch roll 52, can be varied. Any suitable means or construction may be provided for adjusting one of the stops 92, 93 relatively to the other, but in the preferred construction the stop 92 is formed integrally with the actuator 53 so as to be bendable toward or away from the stop 93.

In typewriters or like machines in which all or some of the instrumentalities to be operated, e. g., type bars, carriage return mechanism, tabulating mechanism, escapement mechanism as well as back spacing mechanism, are operated by power, it may be desirable to provide means for varying collectively the extent of driving of the several actuator pawls corresponding to the pawl 69 and associated with the other mechanism referred to. This may be accomplished by providing a knock-off bar 94 mounted on the main frame so as to extend under the front ends of all of the actuators corresponding to the actuator 53 shown in Figure 1. Any suitable means (not shown), may be provided for adjustably tilting or otherwise variably positioning the knock-off bar 94 so that it will be engaged by the lower ends of the actuators to control the timing of disengage-

ment of the associated actuator pawls from the snatch roll.

The train of connections G is so arranged, constructed, and coordinated with the power mechanism E and back spacing mechanism as to suppress or cushion the impact or concussion which otherwise would be transmitted abruptly from the power mechanism E to the back spacing mechanism. Accordingly, undesirable noise and harmful shocks are prevented, and danger of jamming of the machine with resultant damage is eliminated. In the construction shown, a pull link 95 is pivoted as at 96 to the lever 55 and is pivoted as at 97 to a cushioned toggle device generally designated 98. The link 95 preferably is constructed so as to be adjustable as to length, and to this end it comprises parts 95^a and 95^b which may be adjusted longitudinally with respect to each other by an eccentric screw 95^c extending through a slot 95^d in the link part 95^b, and being secured in adjusted position to the link part 95^a. The link parts 95^a and 95^b may be locked in adjusted positions by screws 95^e extending through slots 95^f in the link part 95^b.

The toggle device generally designated 98 includes a toggle lever or link 99 mounted to rock about a fixed pivot 100, and a yoke or lever 101 pivoted as at 102 on the link 99. The yoke 101 includes a part 103 formed with an ear 104 to which is secured one end of a spring 105, the other end of which is secured to an ear 106 on the link 99. The yoke 101 includes another part 107 to which the rear end of the link 95 is pivoted as at 97, as previously stated.

Another toggle link or lever 108 is pivoted at its lower end as at 109 to the link 99, and is pivoted at its upper end as at 110 to the lower end of the thrust link 31. Preferably, the pivot 110 is of a well-known eccentric adjusting type.

Normally, the parts are in the positions shown in Figure 1, wherein the toggle link pair constituted by the links 99 and 108 is "broken" and the thrust link 31 consequently is in its lower or normal position. When the key F is depressed so as to cause the actuator mechanism E to rock the lever 55 counterclockwise in the manner previously described, the link 95 will be pulled forwardly, or to the left as viewed in Figure 1. This will rock the interponent yoke part 101 momentarily about its pivot 102 on the toggle link 99 until the spring 105 is tensioned, whereupon force will be transmitted through the spring 105 to the toggle link 99 to rock the latter counterclockwise about the fixed pivot 100. In this manner the toggle link pair constituted by the links 99 and 108 will be straightened or moved to the position shown in Figure 3, causing the thrust link 31 to be moved upwardly, thereby operating the back spacing mechanism shown in Figures 4 and 5 in the manner previously described. The sudden impulse caused by quick engagement of the actuator pawl 69 with the snatch roll 52 will be transmitted to the link 95 so as to accelerate the latter quickly, but since the actuating force is transmitted through the cushion spring 105 to the toggle pair 99-108, the starting of upward movement of the thrust link 31 will momentarily be gradual so as to avoid harmful shocks in the operation of the back spacing mechanism. By the time the spring 105 has been fully tensioned by rocking of the interponent part 101 about the pivot 102, the thrust link 31 will be in its full upward movement, and the back spacing tooth 41 will have

moved into engagement with the rack 6. Then, because of the still broken condition of the toggle device 98, the link 31 will be moved relatively rapidly so as to effect back spacing. As the toggle links 99 and 108 approach their straightened positions as shown in Figure 3, the thrust link 31 will be decelerated, thereby slowing down the back spacing movement of the carriage and bringing it gently to rest. Overthrow movement of the toggle device 98 is prevented by engagement of a stop projection 111 on the link 108 with a stop ear 112 on the link 99. The mutually engageable stops 111 and 112 limit the operation of the back spacing mechanism, but any continued driving movement of the link 95 following engagement of the stops will be dissipated in or absorbed by expansion of the toggle cushion spring 105. At or near the conclusion of the back spacing movement, the pawl 69 will become disengaged from the snatch roll 52 in the manner previously described and the spring 63 will return the mechanism E and connection train G to their starting positions.

If the key F should be depressed and the actuator 53 and pull link 95 operated when the carriage is blocked at the limit of its return travel by the usual margin stop equipment, with resultant blocking of the thrust bar 36 and associated parts of the back spacing mechanism, the spring 105 will yield to enable the link 95 to reciprocate idly without jamming or damaging the parts.

The mechanism disclosed embodies the invention in a preferred form, but it is intended that the disclosure be illustrative rather than definitive, the invention being defined in the claims.

We claim:

1. In power operating mechanism for a typewriter or like machine, a carriage back spacing mechanism; a driving member; an actuator; means including a cushioned motion-transmitting connection interposed between said actuator and said back spacing mechanism; an interponent mounted on said actuator for movements into and out of operative engagement with said driving member and being biased to move into engagement therewith; a trigger normally maintaining said interponent disengaged from said driving member; a manually operable back spacing control element; means responsive to depression of said element for actuating said trigger to release said interponent and enable it to move into engagement with said driving member, whereby said actuator will be driven by said driving member so as to operate said back spacing mechanism; and trigger re-setting means effective upon return movement of said element when said driving member is stationary for moving said trigger reversely to its releasing movement and thereby disengaging said interponent from said driving member.

2. In a power operating mechanism for a typewriter or like machine; a carriage back spacing mechanism; a rotatable driving member; a movably mounted actuator; means including a cushioned motion-transmitting connection interposed between said actuator and said back spacing mechanism; an interponent mounted movably on said actuator; a spring urging said interponent to move into drive-transmitting engagement with said driving member; a trigger mounted movably on said actuator and normally occupying a position in which it maintains said interponent out of drive-transmitting engage-

ment with said driving member; an abutment; and manually controlled means for imparting to said actuator sufficient initial movement to move said trigger into engagement with said abutment to thereby move said trigger on said actuator and release said interponent to enable the latter to be moved by said spring into drive-transmitting engagement with said driving member, whereby said actuator will be driven by said driving member so as to operate said back spacing mechanism.

3. In a power operated typewriter or like machine, a carriage back spacing mechanism; a driving member; a train of connections between said driving member and said back spacing mechanism including an actuator drivable by said driving member, a first pivoted lever, means connecting said lever to said back spacing mechanism, a second lever, means pivotally mounting said second lever on said first lever at a point spaced from the pivotal axis of said first lever, a force transmitting and cushioning spring interposed between and connecting said levers, and means operatively connecting said second lever to said actuator and being operable by said actuator to rock said second lever whereby to transmit force through said spring to said first lever to rock the latter and operate said back spacing mechanism; and manually operable means for controlling transmission of drive from said driving member to said actuator.

4. In a power operated typewriter or like machine, a carriage back spacing mechanism; a continuously driven rotary toothed snatch roll; a train of connections between said snatch roll and said back spacing mechanism including an actuator normally disconnected from said snatch roll but being controllably connectable therewith substantially instantaneously, whereupon the actuator is abruptly accelerated from rest position, a first pivoted lever, means connecting said lever to said back spacing mechanism, a second lever, means pivotally mounting said second lever on said first lever at a point spaced from the pivotal axis of said first lever, a force transmitting and cushioning spring interposed between and connecting said levers, and means operatively connecting said second lever to said actuator and being operable by said actuator to rock said second lever whereby to transmit force through said spring to said first lever to rock the latter and operate said back spacing mechanism; and manually operable means for controlling connecting of said actuator to said snatch roll.

5. In a power actuated typewriter or like machine, a carriage back spacing mechanism; a driving member; a train of connections between said driving member and said back spacing mechanism including an element operable by said driving member, and a toggle device constituted by two toggle links pivoted together and respectively connected to said element and said back spacing mechanism; mutually engageable stop parts on said links for limiting straightening of the toggle device; and manually operable means for controlling transmission of operating effort from said driving member to said element.

6. In a power operated typewriter or like machine, a carriage back spacing mechanism; a driving member; a train of connections between said driving member and said back spacing mechanism including an element operable by said

driving member, a toggle device constituted by two toggle links pivoted together, means connecting one of said links to said back spacing mechanism, mutually engageable stop parts on said links for limiting straightening of the toggle device, and a cushioning force transmitting spring interposed between said element and the other of said links; and manually operable means for controlling transmission of operating effort from said driving member to said element.

7. In a power operated typewriter or like machine, a carriage back spacing mechanism; a driving member; a train of connections between said driving member and said back spacing mechanism including an element operable by said driving member, a first toggle link mounted to rock about a fixed pivot, a second toggle link pivotally connected to said first toggle link and to said back spacing mechanism, an interponent pivotally mounted on said first toggle link, means connecting said interponent to said element to be operable thereby, and a cushioning force transmitting spring interposed between said interponent and said first toggle link; and manually operable means for controlling transmission of operating effort from said driving member to said element.

8. In a power operated typewriter or like machine, a carriage back spacing mechanism; a driving member; and a train of connections between said driving member and said back spacing mechanism including an element operable by said driving member, a first toggle link mounted to rock about a fixed pivot, a second toggle link pivotally connected to said first toggle link and to said back spacing mechanism, an interponent pivotally mounted on said first toggle link, means connecting said interponent to said element to be operable thereby, a cushioning force transmitting spring interposed between said interponent and said first toggle link for rocking the latter to straighten the toggle formed by said two links and thereby operate said back spacing mechanism, and mutually engageable stop parts on said links for limiting straightening of the toggle.

9. In a typewriter or like machine, a carriage back spacing mechanism; an operating member; and a train of connections between said operating member and said back spacing mechanism including a first toggle link mounted to rock about a fixed pivot, a second toggle link pivotally connected to said first toggle link and to said back spacing mechanism, an interponent pivotally mounted on said first toggle link, means connecting said interponent to said operating member to be operable thereby, and a cushioning force transmitting spring interposed between said interponent and said first toggle link.
